UNITED STATES PATENT OFFICE.

JOHN LEWIS MILTON, OF CLEVELAND, OHIO, ASSIGNOR, BY MESNE ASSIGNMENTS, TO THE TEAGLE COMPANY, OF CLEVELAND, OHIO, A CORPORATION OF OHIO.

MAGNETO-IGNITION SYSTEM FOR INTERNAL-COMBUSTION ENGINES.

1,423,672.

Specification of Letters Patent. Patented July 25, 1922.

Application filed February 18, 1913, Serial No. 749,173. Renewed December 16, 1920. Serial No. 431,096.

To all whom it may concern:

Be it known that I, JOHN L. MILTON, a citizen of the United States, residing at Cleveland, in the county of Cuyahoga and State of Ohio, have invented a certain new and Improved Magneto-Ignition System for Internal-Combustion Engines, of which the following is a full, clear, concise, and exact description, reference being had to the accompanying drawings, forming a part of this specification.

My invention relates to magneto ignition systems for internal combustion engines and one object is to produce a hotter spark than usual with comparatively less expensive apparatus than ordinarily used for this purpose.

Another object is to construct the generator pole pieces and armature pole shoes so as to alter the normal wave form for the purpose of giving an increased effective timing range. The fundamental principles of this construction are disclosed in my United States application Serial Number 475,170, filed Jany. 30th, 1909 (see Letters Patent No. 1,366,475).

Another object of the invention embodied in this ignition system, relates to the compact construction and method of mounting the external transforming coil, on its non-magnetic core.

An instance of my invention is illustrated in the accompanying drawings, in which:

Fig. 1 is a diagrammatic representation of the circuit, Fig. 2 is a combined end elevational and cross sectional view from the driving end of the magneto; (the cross sectional view reveals the distributor and brush holder construction), Fig. 3 is an elevational view of the timer end of the magneto without the cover and with the cover holding spring removed in order to reveal the timer mechanism, Fig. 4 is a vertical axial sectional view of the generator showing the condensers, timer, armature and portions of the distributor mechanism, Fig. 5 is a cross sectional view, (on enlarged scale), of the spark gap, binding post and part of the condenser mounting, Fig. 6 is a detail view of the driving spindle, showing the distributor mounted thereon and Figs. 7 and 8 are elevational and cross sectional views of the transformer coil.

Like reference characters are applied to

the same parts throughout the various figures.

Referring first to Fig. 1, it will be seen that the current is supplied by means of a generator G which is provided with a rotatable core R and the armature coil W wound thereon. One terminal of the winding W is connected to the distributor segment A by means of screw 45^a which also makes electrical contact with one side of the condenser F. Two distributor brushes, a—b, which are radially related connect by means of wires a¹ and b¹ to the primary and secondary of coils C—C. The other terminal of the winding W is grounded by means of a conductor, U.

I illustrate the spark gap terminals which are disposed inside the cylinders at s, s. The arrangement illustrated is for a 4 cycle, 2 cylinder engine. The current generated by the generator G is a relatively low tension current and in order that the high tension current may be supplied to the main spark gap terminals s—s, I provide transformer coils G—G, comprising a primary winding P and a secondary winding S, which are of such construction that they may withstand considerable heat and may therefore be mounted on the engine cylinder or directly on the spark plug. It will be readily observed that the greater part of the circuit is required to carry merely a low tension current. This transformer coil is preferably coreless and the primary winding is disposed outside the secondary winding. The primary winding and the secondary winding have a common connection at T¹ while the screw M forms the other terminal of the secondary winding. The screw M is connected by means of a conductor to the conductor which passes through the insulating sleeve in the spark plug, the inner end of which serves for one terminal of the spark gap inside of the cylinder.

Each of the transformer coils has the terminal which is common to both the primary and secondary windings connected with a respective contact of the distributor, the other terminal of the secondary winding as before stated, is connected with one of the terminals of the spark gap, while the other terminal of the spark gap is grounded as indicated. The other terminal of each primary

winding is connected to a conductor g , which terminates either at the spark gap X in the primary circuit or in the condenser E , the latter method is the preferred form and is 5 illustrated in Fig. 1.

The timing device is in shunt of the generator winding W . The condenser F is also in parallel connection or placed directly across the generator winding.

- 10 The magneto machine which I have illustrated diagrammatically at G in Fig. 1 and which is shown in some detail in Fig. 4, is a conventional type shuttle wound armature with the exception of the dampening coils 15 diagrammatically shown at q and r which are used for the purpose of retarding magnetic changes at the various speeds. These may be used either on the armature or pole pieces, or, they may be used jointly. These 20 retarded magnetic changes are to increase the effective timing range. There can be seen by the diagrammatical representation, Fig. 1, that the dampening rings $r-r$ on the armature are so co-related with the pole 25 pieces that a complete change of the magnetic lines of force cannot suddenly take place. The same diagrammatic representation discloses the pole pieces so arranged as to effect a corresponding condition.
- 30 The illustrations 2, 3 and 4 are full size and drawn substantially to scale. The pole frame is indicated at 6 and the two horseshoe magnets which are associated therewith are shown at 6¹. The usual form of construction is followed on the base and end plates, which carry the bearings, on which 35 rotate the armature spindles. One spindle, 11, carries the cam O , which actuates the timing lever h , the timing lever carries the 40 platinum point h , which registers with platinum point h^1 which is mounted on suitable screw, h^2 , which is in turn supported by the insulated pedestal 28. The spring 29 makes electrical contact with insert 30 of the bakelite timer cover 31, and the insert 30 makes electrical contact through supporting spring 32, which is pivoted on pin 33 which in turn is mounted on a conductor block 34 which is mounted in a 50 bakelite casing 35. Connecting screws 36-36, make electrical contact with a supporting member 37 which carries the condenser E , and makes electrical contact with one terminal of same. This end of the condenser is connected to binding post 38 conveniently placed to receive two wires $g-g$, the ends of which are shown in Fig. 2. The other end of the condenser is connected to a flat conductor, 39, shown in detail in Fig. 5, 55 which shows very clearly the detail construction of the method of securing the second terminal of the condenser E to the condenser supporting plate 40. The condenser, its terminals and the fixed spark 60 gap 41 are assembled completely, independ-

ent of the remainder of the machine. The tongue 42 of the condenser plate fits into a recess of the cover 43 so as to avoid the necessity of providing a more complicated means of holding. The other end of condenser plate 40 is held in place by means of the screws 36, above referred to. The armature construction in addition to that above referred to is novel inasmuch as the spindle 44, which carries the non-magnetic armature end, 45, also carries the condenser F . The screw 45^a serves the triple purpose of holding the condenser in place, carrying the armature current from the insulated end of winding W to the segment A of the distributor, and also of helping to hold the distributor insulation 46 in its proper place. Similarly, the screw 45^b serves the triple purpose of helping to hold the condenser F in place, connecting one terminal of said condenser to ground and helping to hold the insulation 46 in place. Screws 47 serve to secure the end part 45 of the armature to the body thereof. It is shown in Fig. 6 that the insulation 46 is so shaped as to permit 90 the manipulation of screws 47 without disturbing the electrical or mechanical relation of the condenser and distributor. This is very economical construction and is practicable inasmuch as this distributor does 95 not carry high tension current.

Figs. 7 and 8 show the transformer coil which I prefer to use in connection with this system, though any other suitable form of construction can be employed. The coil, 100 in manufacture, is formed on a fibre tube 50, into which an insert, 51, is placed before the first steps of the impregnation of the winding. This insert 51 is provided with a threaded hole so as to make it readily attachable to any part of the engine, either directly or by means of a bracket. In the other end of the tube 50 is placed the insert 105 M which forms the inner end of the secondary winding. This end is connected to 110 the spark plug either directly or through the means of a suitable conductor.

Having described the points of the magneto and circuit which differ from the conventional types of this class of ignition apparatus, I wish to enter into a further explanation of my theory of the operation of the circuit which is illustrated in Fig. 1. I do not wish to be limited to this particular circuit, as this magneto and coil may be 115 operated on various circuits. The circuit disclosed here, by means of the timer lever h and cam O cause a local or direct short-circuit on the armature W by means of wires u and u^1 , and e and e^1 . In the course of 120 operation as the armature rotates the timer interrupts the armature winding at about its maximum electromotive force. The condenser F , being in parallel with the winding and the timer, is immediately charged and 125 130

then instantly begins its discharge through the easier path presented to it, which is through the primary of one of the transformer coils which is in series with the condenser E and spark gap X. I believe that it is the first condenser oscillation which generates a high frequency in the secondary winding of the transformer coil, which is associated with the primary, and through which the condenser has at least partially discharged, the high frequency current having once ionized the spark gap, s, a low resistance path is at once offered to the electrical energy present in the low tension circuit. A very large intense arc being created at s, I believe that it is caused by the non-dissipated current in the armature, together with, possibly, the after oscillations of the condenser. Somewhat similar results are given by this circuit when the condenser E is entirely removed. Under this condition the condenser F discharges at least a part of its oscillation directly through the primary of the transforming coil and across spark gap X. By substituting a kick coil and battery of sufficient voltage for the armature and its winding in the above described circuit, or by substituting a suitable dynamo current, I can secure results similar to those last mentioned. By altering the circuit diagrammatically illustrated in Fig. 1 so as to eliminate the transforming coils and condenser E and use the auxiliary spark gap, X, as a spark plug electrodes with its usual spark gap I can successfully ignite an explosive mixture.

Having made various combinations of this circuit, together with different proportions and different features which do not substantially change the result I do not wish to be limited beyond the appended claims. Many modifications of the features of construction may also be made without substantially producing a new result and on this point I do not wish to be limited beyond the claims attached.

What I claim as new and desire to secure by Letters Patent is:

1. In an ignition generator, the combination with opposite field magnet poles and an armature operatively mounted between the poles, of a cover plate fitting between the said poles, a condenser and a spark gap structure, the said cover plate, condenser and spark gap structure forming a self-contained unit adapted to be assembled before the cover plate is mounted in the generator.

2. In an ignition generator, the combination with opposite field magnet poles and an armature operatively mounted between the poles, of a cover plate fitting between the said poles, a condenser, a spark gap structure and electrical connections for said condenser and structure, the said cover plate, condenser, spark gap structure and electrical

connections forming a self-contained unit adapted to be assembled before the cover plate is mounted in the generator.

3. In a magneto electric machine, the combination with a permanent field magnet and pole pieces secured thereto, of an armature comprising non-magnetic heads, a generating winding, a condenser, an insulated distributor segment, means for fastening the condenser and distributor segment to one of the said heads, and means for securing said head to the body of the armature, the said winding, condenser and segment being electrically connected and the said securing means being adapted to be removed without disturbing the electrical connections.

4. In a magneto electric machine, the combination of a permanent magnet, pole pieces secured thereto, a rotating armature, a timer, a removable cover for said timer, an insulated block carried on the magneto housing, an electrical conducting spring arm pivotally secured to said insulated block and serving to hold said timer cover in place, said spring arm having its cover-holding end normally electrically connected with the timer, and an electrical conductor connected to the spring arm and serving to secure the said insulated block to the magneto housing.

5. In a magneto electric machine, the combination of a permanent magnet, pole pieces secured thereto, a rotating armature, a timer, a condenser, a removable cover for said timer, an electrical conducting spring arm electrically connected with the timer and holding said timer cover in place, an insulating block on the magneto housing to which said electrical conducting spring arm is pivotally secured, and electrical conducting screws serving to secure said block to the magneto housing and make electrical connection between the said spring arm and the condenser.

6. In a magneto electric machine, the combination of a permanent magnet, damped pole pieces secured thereto, and a wire wound armature having damped pole shoes substantially as described and for the purposes set forth.

7. In a magneto electric ignition generator, the combination of a cover plate fitting between the poles of the magneto and carrying the condenser and a self contained spark gap in the primary circuit.

8. In an electric ignition generator, a wire wound armature having damped pole shoes.

9. In an electric ignition generator, an armature having dampening rings surrounding a portion of its periphery.

JOHN LEWIS MILTON.
